FIG. 1.

FIG. 2.

FIG. 3.

INVENTOR
ALBERT BLOM,
BY ATTURNEYS
ATTORNEYS

UNITED STATES PATENT OFFICE.

ALBERT BLOM, OF BUENOS AIRES, ARGENTINA.

GLOVE.

Application filed December 6, 1921. Serial No. 520,380.

To all whom it may concern:

Be it known that I, ALBERT BLOM, a subject of the King of Sweden, residing at Calle Maipú 671, Buenos Aires, Argentina, have invented new and useful Improvements in a Glove, of which the following is a specification.

The present invention refers to a new means for covering the finger-tips of the hand with the object of keeping on the pomades that may be applied thereon for the purpose of curing and beautifying the finger-nails. The invention consists of a covering somewhat similar in its construction to the form of a glove, which can be made of any suitable material, its fingers having in the end where they cover the finger-tips, an opening large enough to allow the respective fingers of the hand to pass through.

10 The object of the said openings is to allow the easy application of pomades or medicaments to the nails and at the same time to enable them to remain covered all the time it may be deemed convenient without any danger of the said products being spread out and lost when the glove is put on, also preventing the carrying of the said medicaments to places where they are not necessary and thereby annulling all the effects of the treatment.

20

As it will be readily understood, the material to be used as well as the invention as a whole, may be altered without affecting the novelty of the invention.

25 Up to now, loose fingers easily lost or drawn off, have been used, thus annulling the effects of treatments, or else common gloves for the purpose of keeping the products on the finger-nails during the whole time in which they are submitted to the treatment.

The inconvenience resulting from such means is that once the finger-nails are covered with the pomade, it is impossible to avoid the medicament being drawn off by the material of the glove when the latter is put on, it being then impossible to obtain the desired effect from the treatment, besides the fact that the inside of the glove gets spoilt.

50 Through the present invention such inconveniences are done away with by means of an opening or cut made in the end that covers the finger-tips. In this way it is possible and easy to put on the glove first, taking care that the finger-tips remain un-

covered by means of the above mentioned openings, and that the medicament is applied to the finger-nails in such way that once the operation is made, the finger-tips 60 can be covered with the ends of the glove's fingers, and then everything adjusted, fitted in and pressed close with complete facility.

The new method, by means of such openings and finger ends arranged on the hand 65 in a way similar to a glove, does away, therefore, with the disagreeable effects resulting from the use of closed gloves.

In order that the present invention may be clearly understood, a drawing is attached 70 to the present specification in which three models of gloves manufactured according to the present invention, are shown, but it must be borne in mind that the illustrations therein are only for the purpose of providing an example; as it has already been stated, the way of fastening the finger coverings to the hand, can be varied according to requirements.

In Figure 1, the glove (1) is of common 80 manufacture, its innovation consisting of the slots (2). The upper part of said openings shows a leaf (3) which enables the fixing of the ends covering the respective finger-tips.

In Figure 2, the palm of the glove has been eliminated joining the finger coverings together in a band (4) which with the aid of ribbons (5) is tied to the wrist and fastened therein through a locket, clasp, 90 etc.

Figure 3 shows a glove in which its finger openings are in form of an incision made longitudinally to the respective finger, the palm of the glove shewing also a longitudinal opening, these openings being also closable through pressure buttons or any other suitable means.

As it can be easily understood, the gloves or finger coverings can be made of any kind 100 of skin, rubber, cloth, etc.

Having thus described and specified the nature of the present invention and the means for carrying it into effect, the undersigned claims the following as has own 105 and exclusive invention:

1. Means to keep on the finger-nails all products applied thereto with the object of curing, beautifying, cleaning and preserving the same, which means consists of a glove 110 having openings in its thumb and each finger adjacent the tips thereof to allow the

part which covers the ends of the fingers, to be fixed thereto after the glove has been put on, and the medicaments applied to the finger-nails without spreading the said medicaments.

2. A hand covering for the treatment of the nails, including thumb and finger members, said members each having an opening adjacent the tips on the palm sides there-
10 of, said openings each having a tab at its outer end.

3. A hand covering for the treatment of the nails, comprising a back strip and thumb and finger members, said members each having an opening therein, and tabs formed in 15 the members adapted to project into said openings.

ALBERT BLOM.
